UNITED STATES PATENT OFFICE

2,573,503

HUTCH VALVE FOR BAUM JIGS

William J. Smith, Worthington, Ohio, assignor to
The Jeffrey Manufacturing Company, a corpora-
tion of Ohio

Application October 6, 1949, Serial No. 119,788

5 Claims. (Cl. 209—455)

1

This invention relates to a jig adapted to separate material according to specific gravity, and an object of the invention is to provide improved means in the form of a one-way valve to control the flow of fluid between the hutch compartment and the associated elevator compartment during the cyclic up and down movement of the jiggling fluid.

Other objects of the invention will appear hereinafter, the novel features and combinations being set forth in the appended claims.

In the accompanying drawings,

Fig. 1 is a sectional elevational view of a portion of a jig incorporating the features of my invention;

Fig. 2 is a sectional view showing particularly the control valve of my invention;

Fig. 3 is an elevational view taken on the line 3—3 of Fig. 1, looking in the direction of the arrows;

Fig. 4 is a view, similar to Fig. 2, showing a modified form of control valve;

Fig. 5 is a view, similar to Fig. 3, of the modified valve; and

Fig. 6 is a sectional view taken on the line 6—6 of Fig. 5, looking in the direction of the arrows.

The general construction of a typical Baum jig is disclosed in the patent to Orval R. Strawn, No. 2,281,530, dated April 28, 1942, to which reference is made for a more complete illustration of the jig illustrated particularly in Fig. 1 of the drawings, with certain modifications to incorporate the features of my invention.

As disclosed, particularly in said Fig. 1, the jig includes a main container 10 in which there is a perforated generally horizontal screen plate 11 upon which a bed of material, such as coal or iron ore, is to be stratified by the cyclic upward and downward movement of the cleaning and stratifying fluid, such as water, through said screen plate 11 and bed of materials supported thereon, in a manner well known in the art of jiggling. The illustrated jig is of the Baum type in which air is periodically admitted to a chamber and exhausted therefrom to effectuate the jiggling action of the water through the bed and screen plate 11 to stratify the material, with the high gravity material in the bottom stratum.

Below the screen plate 11 is a hutch compartment 12 which, as illustrated in the drawings, is divided into two transverse sections by a partition 13. To the left of the hutch compartment 12 there is an elevator compartment 14 within which there is a bucket-type elevator 15 for ele-

2

vating and discharging the high gravity material delivered thereto from the screen plate 11 by the high gravity or refuse control mechanism 16. The jig illustrated is primarily a coal cleaning jig rather than an ore type jig and thus the high gravity control mechanism 16 is designated as the refuse control. An ore jig, while fundamentally similar, is generally smaller and, of course, the high gravity material in the case of an ore jig constitutes the values, the low gravity material the gangue. It will be understood that the invention is applicable to either coal cleaning jigs, ore jigs, or any other type of jig.

There is a partition 17 which separates the hutch compartment 12 from the elevator compartment 14 and constitutes a common wall thereof. Adjacent the bottom of the partition 17 there is an opening 18 through which hutch material collecting in the bottom of the hutch compartment 12 can flow into the elevator compartment 14. Such an opening 18 has heretofore been standard construction. In the Strawn patent above mentioned there is also a screw conveyer in the bottom of the hutch compartment which conveys the hutch material into the boot or bottom of the elevator compartment. Such a screw conveyer is oftentimes not used and is not illustrated in the jig with which my improved apparatus is associated, though, if desired, such a hutch conveyer may be used.

It has been found in practice that where there was an uncontrolled opening between the hutch compartment and the elevator compartment, such as the opening 18, there was an undesirable back flow of separating liquid from the elevator compartment to the hutch compartment during the suction stroke, during which the cleaning water flowed downward through the screen 11 and bed of material thereon. This materially reduced the effectiveness thereof in that considerable of the energy of the suction stroke was employed merely to pump the water up and down in the elevator compartment. I have found that the efficiency of a jig can be very materially increased if this flow of fluid is prevented, while providing for relatively free flow of the fluid from the hutch compartment into the elevator compartment during the pulsion stroke, or, in other words, during the upward movement of fluid through the screen 11 and the bed of material which it supports.

I have provided control valve means 19 in association with the opening 18 to permit relatively free flow of the jiggling liquid during the pulsion stroke from hutch compartment 12 to elevator compartment 14 while restricting or preventing

the free flow of said fluid through the suction stroke. Said control means 19 includes a box type structure 20 which cooperates with the partition 17 and the downwardly sloping bottom portion of the hutch compartment 12 which is adjacent the opening 18 so as to prevent any flow of liquid to and through the opening 18 except through an opening 21 which is provided in said box 20. Said opening 21 is formed between the bottom of a cross channel 22, which forms a part of said box 20, and the bottom of the hutch compartment 12 directly therebelow.

A flexible valve element 23, preferably made of rubber material, such as ordinary rubber belting, is provided, the top of which is rigidly attached as by bolted cross plate 24. The bottom edge of the valve element 23 is normally curved so as to have a wiping contact with the adjacent bottom portion of the compartment 12. The sides of the valve element 23 overlap upstanding side portions of said box 20.

Reinforcing ribs 26 extend laterally downward from the channel 22 to which they are rigidly attached, as by welding, and terminate just above the adjacent bottom wall of the hutch compartment 12. It is evident that whenever the fluid pressure on the right-hand side of the flexible valve element 23 (as viewed in Figs. 1 and 2 of the drawings) is greater than on the left-hand side, valve element 23 will swing to the left and allow the fluid to flow from the hutch compartment into the elevator compartment. This condition will normally exist during the pulsion stroke or as the cleaning liquid moves upward through the screen 11 and bed of material supported thereby. During the suction stroke the pressure on the right-hand side of the valve element 23 will be less than on the left-hand side, whereupon it will swing to the left, as viewed in Figs. 1 and 2 of the drawings, effectively closing the control valve 19 and preventing the reverse flow of the fluid from the elevator compartment 14 into the hutch compartment 12.

In Figs. 4, 5 and 6 of the drawings I have shown an added structure to the valve 19 in the form of an adjustable gate 27 which is mounted for vertical up and down adjustment between guideways on opposite sides thereof, placed in front of the ribs 26 and vertically adjustable by a pair of spaced adjusting screws and cooperating nuts 28.

It is obvious that by adjusting the gate 27 the effective size of the opening 21 may be variably adjusted. This construction has been found desirable in some instances and has the flexible feature of providing control for the fluid flow between the hutch compartment 12 and the elevator compartment 14.

In the operation of the jig, compressed air will be employed to produce the cyclic successive up and down flow of the jiggling fluid or water through the screen plate 11 with the consequent stratification of the bed of materials thereon, with the high gravity material in the bottom stratum and the low gravity material in the top stratum. This operation is essentially a standard one, and the means for producing it are disclosed in detail in the Strawn patent above identified.

The high gravity material will be discharged by the ejector 16 under control of float means generally designated 29, with the low gravity material and some of the clean water flowing through the adjustable height discharge lip 30. During the compression period or period of

upward flow of the water through the screen 11 and bed thereon, the pressure on the right-hand side of the partition 17, as viewed in Figs. 1 and 2 of the drawings, will exceed that on the left-hand side, causing liquid to flow relatively freely through the check valve 19 and opening 18 into the elevator compartment 14. During the suction stroke, or, as the water moves downwardly through the screen 11 and the bed thereon, the check valve 19 will close so as to prevent or greatly restrict the reverse flow of said fluid, or, in other words, the flow of fluid from the elevator compartment 14 into the hutch compartment 12. As a consequence there will be considerably less pulsation of liquid in the elevator compartment 14, or, stated another way, there will be less variation from instant to instant in the liquid level therein. One effect of this will be to require less cleaning fluid, or water. Another effect will be that the energy delivered to the pulsating liquid in the jiggling compartment will be more efficiently employed as considerably less will be involved in periodic raising and lowering the liquid level in the elevator compartment 14 for no particular purpose. In short, there will tend to be more suction on the bed because of the presence of the valve 19, with the same amount of jiggling energy employed.

Other features of the jig are not described in detail as they are shown in the Strawn patent above identified, and, per se, constitute no part of the instant invention.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A jig including a material supporting screen, a hutch compartment below said screen, an elevator compartment communicating with said hutch compartment, and check valve means for restricting fluid flow from said elevator compartment to said hutch compartment while providing for relatively free fluid flow from said hutch compartment to said elevator compartment.

2. A jig including a material supporting screen, a hutch compartment below said screen, an elevator compartment communicating with said hutch compartment, and check valve means for preventing fluid flow from said elevator compartment to said hutch compartment while providing for relatively free fluid flow from said hutch compartment to said elevator compartment.

3. A jig including a material supporting screen, a hutch compartment below said screen, an elevator compartment communicating with said hutch compartment, and variable size check valve means for restricting fluid flow from said elevator compartment to said hutch compartment while providing for relatively free fluid flow from said hutch compartment to said elevator compartment.

4. A jig adapted to stratify material in a bed by pulsating upward and downward movements of water through said bed including a jiggling compartment having a bed supporting screen and a hutch compartment therebelow, an ele-

vator having a compartment adjacent said jigg-
ing compartment, high gravity material eject-
or means adjacent said screen controlling the
ejection of high gravity material from said screen
into said elevator compartment, means provid-
ing a fluid passageway between the bottom of
said hutch compartment and said elevator com-
partment, and a one-way adjustable check valve
operable to restrict the flow of fluid from said
elevator compartment into said hutch compart-
ment during the downward movement of the
water through said bed and operable to permit
free flow of fluid from said hutch compart-
ment into said elevator compartment during the
upward movement of the water through said
bed.

5. A jig adapted to stratify material in a
bed by pulsating upward and downward move-
ments of water through said bed including a
jigg-
ing compartment having a bed supporting
screen and a hutch compartment therebelow, an
elevator having a compartment adjacent said
jigg-
ing compartment, high gravity material eject-
or means adjacent said screen controlling the
ejection of high gravity material from said screen
into said elevator compartment, means providing
a fluid passageway between said hutch com-

partment and said elevator compartment, and a
one-way check valve operable to restrict the flow
of fluid from said elevator compartment into
said hutch compartment during the downward
movement of the water through said bed and
operable to permit free flow of fluid from said
hutch compartment into said elevator compart-
ment during the upward movement of the water
through said bed.

WILLIAM J. SMITH.
